UNITED STATES PATENT OFFICE

2,191,717

VACUUM CLEANER

Harry A. Jeffery, Cleveland Heights, Ohio

Application February 11, 1937, Serial No. 125,225

1 Claim. (Cl. 230—95)

This invention relates to the art of vacuum cleaners and is especially applicable to the cleaning of automobile upholstery as it is adapted to be operated by the air pressure universally found at automobile service garages and service stations.

The object of this invention is to provide a device that is readily portable and can be connected to and operated by the familiar air pressure supply at any point for efficiently removing the dirt from automobile upholstery and depositing the same in a container which can be emptied from time to time.

A further object is to provide such a device with a sight glass which is so arranged that the flow of dirt can be actually seen as it is extracted from the automobile upholstery and discharged through this device.

Another object is to provide such a device with an efficient form of baffle means for diverting and directing the flow of the dirt-laden air as it is forced into the container and the dirt deposited therein.

More specifically, the object is to devise a readily portable vacuum cleaning apparatus comprising a container holding water for the discharge of the dirt thereinto, and with an attachment therefor which has suitable connecting means for air pressure supply and for the hose and tool through which the dirt is drawn by the force of the air pressure and deposited in the water within the container.

Other objects will appear from the following description and claims when considered together with the accompanying drawing.

Fig. 1 is a view, partly in elevation and partly in section, illustrating my complete assembly;

Fig. 2 is a sectional view of the attachment for connecting the means of air pressure and the hose and tool for cleaning; and

Fig. 3 is a view taken on line 3—3 of Fig. 2.

It is to be understood that the present form of disclosure is merely for purposes of illustration and that there may be devised various modifications without departing from the spirit of the invention as herein described and claimed.

Referring to the accompanying drawing, the container 1 is adapted to be filled with water to the level of the pet cock 2 and has the drain plug 3 by which it can be emptied from time to time. This container which can be in the form of a cylindrical galvanized drum or any other suitable form, has the removable head 4 which is secured in place by the ring 5 and has any desired number of apertures 6. There is also a wire

screen 7 mounted within the upper part of the container. Apertures 6a may also be provided around the upper part of the container.

Briefly, the purpose of this container is to receive the dirt-laden air from which the dirt is deposited into the water and the air permitted to escape through the apertures in the top part of the container, as will be more fully explained.

The center of the head 4 has screw-threaded connection with the upper end of the pipe 8 which has threaded onto its lower end the conical shield 9 which in turn has attached thereto, as at 10, the conical baffle member 11. As will be seen, the lower edges of these members 9 and 11 are spaced from the level of the water and their purpose is to divert and direct the dirt-laden air as it is discharged from the pipe 8. The shield 9 extends slightly below the baffle 11 in order that the dirt-laden air will be directed into the water for depositing the dirt before the air is deflected upwardly towards the top of the container. Because of the increased area provided by the passage between the members 9 and 11, the pressure of the air will be here reduced while at the same time the dirt-laden air will be directed effectively towards the water and over an increased area thereof for depositing the dirt which will be held by the water.

The screen 7, which might be replaced by a perforated plate, will prevent the escape of dirt upwardly.

The restricted throat member 13 has screw-threaded connection with the upper end of pipe 8 and has screw-threaded connection also with the lower end of the attachment 14 into which it extends so as to form part of an injector.

The attachment 14 has the screw-threaded opening 15 for connection of an air pressure supply pipe 15a, and from this opening 15 there extends the tube 16 in spaced relation within the attachment 14 and terminates in the injector nozzle 17 in co-operation with the restricted throat member 13. The nozzle 17 terminates at a distance from the spreading inlet of the throat in member 13 so as to force into and through the member 13 the dirt-laden air which is drawn into the chamber of the attachment 14 through the upper end thereof, according to the present illustration.

At the upper end of the attachment 14 there is screw-threaded connection for the angular-shaped member 18 to which is connected the flexible hose 19 carrying the familiar tool 20. In the present form of illustration, the arms of member 18 are at about forty-five degrees to each other.

and a sight window is removably mounted so as to permit an observation of the dirt as it is drawn past this point. The window 21 is of spherical form and is secured in place by means of a screw 5 ring.

At the turn in the member 18 there is a rib 18a which serves as a baffle in diverting the dirt-laden air so as to deflect it against the glass window 21. In this way, the dirt will be caused 10 to swirl about this elbow and this will enable the dirt to be viewed through the window 21. Thus the presence and approximate quantity of dirt can be readily determined at any time during operation of the device.

15 The opening which is closed by screw plug 22 permits access to the parts for assembly and inspection of the same, and the opening that is closed by screw plug 23 may be used for connection of the member 18 if so desired instead 20 of at the point indicated in the drawing. In case of such change, the opening in the upper end of the attachment 14 would be closed.

The average air pressure found today in the automobile service garage is about 150 pounds 25 which, with my device, will afford very strong suction. In fact, actual experience has shown that it is possible to clean much more thoroughly with my present device than with other devices now on the market.

30 Furthermore, the use of my device does not involve the use of any mechanical or electrical motive means; the suction is supplied entirely by

the force of the air pressure already available at the average garage or service station and there is no other expense involved in the use of my device, which is therefore not expensive to operate. Also, this device can be manufactured and sold at a comparatively low price. 5

Another distinguishing characteristic of my device is the fact that it is much more sanitary than the familiar type of vacuum cleaner which employs a cloth bag to receive and hold the dirt. 10

Other advantages will readily suggest themselves to those who are familiar with the art to which this invention relates.

What I claim is:

In a device of the class described, a single form 15 of attachment having an inlet connection for entrance of a fluid under pressure, said inlet continuing in the form of a tube having an injector nozzle within the attachment, said attachment having formed therein an intake connection 20 through which dirt-laden air may be drawn at a point substantially to the rear of the nozzle, said attachment having a restricted discharge opening through which the dirt-laden air may be expelled in a direct manner by the 25 force of the fluid pressure from the nozzle, and means provided upon the lower end of the attachment for connecting the same in an upright position upon a container for discharging 30 the dirt-laden air thereinto.

HARRY A. JEFFERY.
